US0D1075603S

(12) **United States Design Patent** (10) **Patent No.:** **US D1,075,603 S**
(45) **Date of Patent:** **** May 20, 2025**

(54) **PEDAL ACTUATOR**

- (71) Applicant: **BG Intellectuals, Inc.**, Wichita, KS (US)
- (72) Inventors: **Michael Jason Erwin**, Augusta, KS (US); **Thomas Michael Probus**, Wichita, KS (US); **Bradley Robert Young**, Wichita, KS (US); **Stephen Pederson**, Wichita, KS (US); **Zachary Dold**, Wichita, KS (US)
- (73) Assignee: **BG Intellectuals, Inc.**, Wichita, KS (US)
- (**) Term: **15 Years**
- (21) Appl. No.: **29/857,480**
- (22) Filed: **Oct. 21, 2022**
- (51) LOC (15) Cl. **12-16**
- (52) U.S. Cl. **USPC D12/180**
- (58) **Field of Classification Search**
USPC D12/180, 174, 179, 400; D13/112; D15/148, 199
CPC F16H 25/186; F16H 61/28; H02K 7/06; H02K 7/1166; B60K 26/02; B60S 5/00

(57) **CLAIM**

The ornamental design for a pedal actuator as shown and described.

DESCRIPTION

FIG. 1 depicts a back, top, right side perspective view of a pedal actuator showing the claimed design.

FIG. 2 depicts a front, bottom, left side perspective view thereof.

FIG. 3 depicts a front view thereof.

FIG. 4 depicts a back view thereof.

FIG. 5 depicts a top view thereof.

FIG. 6 depicts a bottom view thereof.

FIG. 7 depicts a left side view thereof; and,

FIG. 8 depicts a right side view thereof.

The long-short dash lines depict boundaries of the claimed design and form no part of the claimed design. The even dash lines depict portions of the pedal actuator forming no part of the claimed design.

1 Claim, 8 Drawing Sheets
